Inventor
C.C.Rodery.

Attaduply Jr. Attorney

UNITED STATES PATENT OFFICE.

CONOE C. RODERY, OF HORNERSVILLE, MISSOURI.

CHAIR ROCKER.

Application filed April 16, 1925. Serial No. 23,635.

This invention relates to chair rockers, and has for one of its objects the provision of a novel, simple and inexpensive device of this character which will not when in use cut carpets, rugs and other floor coverings, and which shall be adapted for application to chairs of different sizes.

A further object of the invention is the provision of a device of the character stated which can be readily made of metal and which shall be neat and attractive in appearance.

With the foregoing and other objects in view, the invention consists of the construction, combination and arrangement of parts hereinafter fully described and claimed, and illustrated in the accompanying drawing, wherein:

Figure 1 is a view in side elevation of a rocking chair equipped with rockers constructed in accordance with my invention,

Figure 2 is a detail top plan view of the rocker,

Figure 3 is a detail sectional view taken on the plane indicated by the line 3—3 of Figure 2,

Figure 4 is a similar view taken on the plane indicated by the line 4—4 of Figure 2,

Figure 5 is a sectional view taken on the plane indicated by the line 5—5 of Figure 1, and

Figure 6 is a detail sectional view taken on the plane indicated by the line 6—6 of Figure 2.

Corresponding and like parts are referred to in the following description, and designated in the several views of the accompanying drawing, by similar reference characters.

In the drawing, 1 designates the seat, 2 the back, 3 the legs, and 4 the rockers of a rocking chair.

The rockers 4 are made of metal and comprise bases 5 which are of considerable width and strengthening ribs 6 which extend centrally and longitudinally along the upper sides of the bases 5. The ribs 6 are corrugated vertically to add strength and rigidity thereto. Each rocker 4 is preferably made from a single strip of light sheet metal, and in the manufacture of the rocker the side portions of the metal strip are bent inwardly upon the central portion thereof to provide the base 5. The side portions of

the metal strip are thence bent at right angles to the base 4 and brought together to form the ribs 6, after which the rib 6 is corrugated. The side edges of the bases 5 are rounded as indicated at 7 to prevent the rockers 4 from cutting carpets, rugs and other floor coverings. Guards 8 formed integrally with the rear ends of the bases 5 and inclined upwardly and forwardly, contact with the beveled upper edges 9 of the rear ends of the ribs 6 and embrace the sides of said ends of the ribs as shown in Figure 3. The guards 8 reinforce the rear ends of the rockers 4 and have no sharp edges liable to cause damage to other articles of furniture and floor coverings. The front ends of the ribs 6 are beveled as indicated at 10, and the front ends of the bases 5 are bent upon themselves as indicated at 11 whereby to increase the thickness of the front ends of the bases 5 so as to avoid sharp edges that would cause damage to other articles of furniture.

Sockets 12 for the reception of the lower ends of the chair legs 3 rest at their lower ends upon the upper edges of the ribs 6 and are provided with slotted stems 13 which receive the ribs 6 and which are secured thereto by bolts 14. To permit the rear sockets 12 to be secured at different points in the lengths of the ribs 6, the latter are provided with a plurality of bolt receiving openings 15. The legs 3 are secured in the sockets 12 by screws 16.

From the foregoing description, taken in connection with the accompanying drawing, it should be apparent that the rockers may be readily secured to or removed from a chair, that they may be secured to chairs of different sizes, and that they will not cause damage to other articles of furniture and floor coverings.

It should be understood that the drawing is merely illustrative and does not pretend to give exact proportions. Furthermore, the said drawing is illustrative of a preferred construction, it being my expectation that various changes and modifications may be made without departing from the spirit and scope of the invention.

What is claimed is:

1. A rocker comprising a base, portions returned over said base, ribs in contact with each other and rising from said portions at

a point between the sides of the base, and integral guards at the ends of the rocker engaging said ribs to reinforce them.

2. A rocker comprising a base, portions ⁵ turned over said base, ribs in contact with each other and rising from said portions at a point between the sides of the base, and

integral guards at the ends of the rocker engaging said ribs to reinforce them, one of the guards having portions engaging opposite sides of the ribs and the other guard extending across end edges of the ribs. ¹⁰

In testimony whereof I affix my signature.

CONOE C. RODERY.
